FACIAL PATTER

Jacob Knapp, Newark, N. J.

Application July 21, 1931, Serial No. 552,135

5 Claims. (Cl. 128—54)

This invention relates to patters and has as its object to provide a facial patter having means for removably securing thereto a pad of novel construction for the reception of astringents, lotions and antiseptics for application to the face or other parts of the body especially after a "facial" has been received at a "beauty parlor".

Another object of my invention is to provide the patter with means adjustably arranged 10 in the handle thereof, for regulating the vibratory movement of the patter.

Another object of my invention is to provide an individual pad for use with a facial patter, which is of a sanitary, hygienic and highly practical construction, and is so formed as to be readily and frequently replaceable, whereby individual pads for use by various individuals and for use by the same individual, for the application of various astringents and lotions, may be 15 provided for.

A further object of my invention is to provide a facial patter of the character set forth consisting of relatively few parts, the parts being easily assembled and readily replaceable, which 20 lends itself admirably to economical manufacture in large quantities by the use of simple tools and dies.

These and other advantageous objects, which will later appear, are accomplished by the simple 25 and practical construction and arrangement of parts hereinafter described and exhibited in the accompanying drawing, forming part hereof, and in which:

Figure 1 represents a front elevational view 30 of my improved patter,

Figure 2 represents a side elevational view thereof,

Figure 3 represents a transverse sectional view taken along lines 3—3 of Fig. 1,

Figure 4 represents a vertical transverse sectional view of the hollow handle employed in my improved patter, provided with a ferrule to which a flat spring is secured,

Figure 5 represents a side elevational view 45 of the adjusting rod used in my patter, and

Figures 6 and 7 represent, respectively, a front and side elevational view of the pad used in my patter.

As shown in the drawing, my device consists, 50 essentially, of the hollow handle 1 having secured thereto, at its upper end, a ferrule 2. A resilient member, preferably in the form of a flat spring 3, is secured at one end in any desired or convenient manner to the ferrule 2, 55 being preferably secured in the slotted end 4 of

the ferrule 2, the other end of the spring being secured in the enlarged slotted head 5 of the shank 6, which has integrally secured thereto the pad supporting disc 7.

Slidably mounted in the hollow handle 1 is 60 an adjusting rod 8, the upper end of which is slotted, at 9, to have sliding engagement with the sides of the flat spring 3. A finger-piece 10 of any convenient shape is secured to the rod 8 in any desired manner, the reduced portion of 65 said finger-piece 10 engaging with a slot 11 in the handle 1 whereby on manipulation of the finger piece 10, the slotted end 9 of the rod 8 is moved up and down on the spring 3 to regulate the swinging movement of the patter. 70

While this structure has been found advantageous for the regulation of the vibratory movement of the pad support, it is within the scope of my invention to utilize other structures for the same purpose. For example, instead of providing a hollow handle in which the adjusting rod 8 is slidable, the adjustment could be accomplished by providing any equivalent means defined by the claims. 75

A pad 12 adapted to receive liquid astringents, 80 lotions, antiseptics and other liquids, is removably secured to the disc 7 by the bezel 13, which preferably has frictional engagement with the periphery of the disc 7, but may be secured thereto by a bayonet-slot or other arrangement 85 (not shown).

The pad 12 may be made of cloth, sponge, felt, paper or the like by the use of suitable punches and dies, but I prefer and have used a circular pad made from surgical cotton, preferably oval 90 in cross-section and which in the course of manufacture is provided with a circumferentially arranged flange 14 formed by compressing the material of the peripheral edge thereof.

This form of pad is especially advantageous 95 in that it lends itself admirably for ready removal from the pad supporting disc and in use pads of this type are constantly replaced by similar pads from time to time.

On manipulating the handle 1, the opposite 100 pad end of the patter will vibrate, due to the intermediate spring 3, and by moving the finger piece 10 of the rod 8 up or down in the slot 11 of said handle 1, the split end 9 of the rod 8 will be selectively moved into engagement with a 105 greater or lesser portion of the length of the spring 3, thus regulating the vibratory movement of the pad end of the patter to suit the type of skin to be patted.

I have shown and described the preferred em- 110

bodiment and forms of my invention, but my invention is to be understood as covering all other variations in structure within the scope of the appended claims.

5 The foregoing disclosure is to be regarded as descriptive and illustrative only, and not as restrictive or limitative of the invention, of which obviously an embodiment may be constructed including many modifications without departing 10 from the general scope herein indicated and denoted in the appended claims.

Having thus described my invention, what I claim as new and desire to secure by Letters Patent, is:

15 1. A patter comprising a handle, a pad support, a spring connecting the support with the handle, and a member slidably connected with said handle and adapted to engage with said spring for regulating the vibratory movement 20 of the pad support.

2. In a patter, a hollow handle having a longitudinal slot, a spring secured to said handle, a bar slidably arranged in said handle and adapted to engage with said spring to regulate the vibratory movement thereof, and a finger-piece on 25 said bar movable in the slot of said handle.

3. In a patter, a handle, a pad support, a spring connecting the support with the handle, and a member slidably connected with the handle and adapted to engage with the spring to regulate the vibratory movement of the pad support.

30 4. In a patter, a handle, a pad support, a spring connecting the support with the handle, and a member slidably connected with the handle and adapted to engage with the spring to regulate the vibratory movement of the pad support.

35 5. In a patter, a handle, a pad support, a spring connecting the support with the handle, and a member slidably connected with the handle and adapted to engage with the spring to regulate the vibratory movement of the pad support.

40 6. In a patter, a handle, a pad support, a spring connecting the support with the handle, and a member slidably connected with the handle and adapted to engage with the spring to regulate the vibratory movement of the pad support.

45 7. In a patter, a handle, a pad support, a spring connecting the support with the handle, and a member slidably connected with the handle and adapted to engage with the spring to regulate the vibratory movement of the pad support.

50 8. In a patter, a handle, a pad support, a spring connecting the support with the handle, and a member slidably connected with the handle and adapted to engage with the spring to regulate the vibratory movement of the pad support.

55 9. In a patter, a handle, a pad support, a spring connecting the support with the handle, and a member slidably connected with the handle and adapted to engage with the spring to regulate the vibratory movement of the pad support.

60 10. In a patter, a handle, a pad support, a spring connecting the support with the handle, and a member slidably connected with the handle and adapted to engage with the spring to regulate the vibratory movement of the pad support.

65 11. In a patter, a handle, a pad support, a spring connecting the support with the handle, and a member slidably connected with the handle and adapted to engage with the spring to regulate the vibratory movement of the pad support.

70 12. In a patter, a handle, a pad support, a spring connecting the support with the handle, and a member slidably connected with the handle and adapted to engage with the spring to regulate the vibratory movement of the pad support.

75 13. In a patter, a handle, a pad support, a spring connecting the support with the handle, and a member slidably connected with the handle and adapted to engage with the spring to regulate the vibratory movement of the pad support.

3. In a patter, a disc, a support for the disc, a circular pad having a body portion of liquid absorbent material, said pad having a circumferential flange of the same material as the body portion, said flange being substantially rigid and compact relative to the body portion, and means to fit over said flange to detachably secure the pad to the disc. 80

4. In a patter, a circular supporting disc, a circular pad having a body portion of liquid absorbent material, said pad having a circumferential flange of the same material as the body portion, said flange being substantially rigid and compact relative to the body portion, a bezel engaging said flange and detachably secured to the disc to hold the pad on the disc. 85

5. In a patter, a circular supporting disc, a pad having a body portion of liquid absorbent material, said pad having a peripheral flange of the same material as the body portion, said flange being substantially rigid and compact relative to the body portion, a bezel engaging said flange and detachably secured to the disc to hold the pad on the disc. 90

6. In a patter, a circular supporting disc, a pad having a body portion of liquid absorbent material, said pad having a peripheral flange of the same material as the body portion, said flange being substantially rigid and compact relative to the body portion, a bezel engaging said flange and detachably secured to the disc to hold the pad on the disc. 95

JACOB KNAPP.

100

7. In a patter, a circular supporting disc, a pad having a body portion of liquid absorbent material, said pad having a peripheral flange of the same material as the body portion, said flange being substantially rigid and compact relative to the body portion, a bezel engaging said flange and detachably secured to the disc to hold the pad on the disc. 105

8. In a patter, a circular supporting disc, a pad having a body portion of liquid absorbent material, said pad having a peripheral flange of the same material as the body portion, said flange being substantially rigid and compact relative to the body portion, a bezel engaging said flange and detachably secured to the disc to hold the pad on the disc. 110

9. In a patter, a circular supporting disc, a pad having a body portion of liquid absorbent material, said pad having a peripheral flange of the same material as the body portion, said flange being substantially rigid and compact relative to the body portion, a bezel engaging said flange and detachably secured to the disc to hold the pad on the disc. 115

10. In a patter, a circular supporting disc, a pad having a body portion of liquid absorbent material, said pad having a peripheral flange of the same material as the body portion, said flange being substantially rigid and compact relative to the body portion, a bezel engaging said flange and detachably secured to the disc to hold the pad on the disc. 120

11. In a patter, a circular supporting disc, a pad having a body portion of liquid absorbent material, said pad having a peripheral flange of the same material as the body portion, said flange being substantially rigid and compact relative to the body portion, a bezel engaging said flange and detachably secured to the disc to hold the pad on the disc. 125

12. In a patter, a circular supporting disc, a pad having a body portion of liquid absorbent material, said pad having a peripheral flange of the same material as the body portion, said flange being substantially rigid and compact relative to the body portion, a bezel engaging said flange and detachably secured to the disc to hold the pad on the disc. 130

13. In a patter, a circular supporting disc, a pad having a body portion of liquid absorbent material, said pad having a peripheral flange of the same material as the body portion, said flange being substantially rigid and compact relative to the body portion, a bezel engaging said flange and detachably secured to the disc to hold the pad on the disc. 135

14. In a patter, a circular supporting disc, a pad having a body portion of liquid absorbent material, said pad having a peripheral flange of the same material as the body portion, said flange being substantially rigid and compact relative to the body portion, a bezel engaging said flange and detachably secured to the disc to hold the pad on the disc. 140

15. In a patter, a circular supporting disc, a pad having a body portion of liquid absorbent material, said pad having a peripheral flange of the same material as the body portion, said flange being substantially rigid and compact relative to the body portion, a bezel engaging said flange and detachably secured to the disc to hold the pad on the disc. 145

16. In a patter, a circular supporting disc, a pad having a body portion of liquid absorbent material, said pad having a peripheral flange of the same material as the body portion, said flange being substantially rigid and compact relative to the body portion, a bezel engaging said flange and detachably secured to the disc to hold the pad on the disc. 150
